UNITED STATES PATENT OFFICE.

PERCY DE HAAS, OF ROCK FERRY, ENGLAND.

DISK TALKING-MACHINE.

1,369,269.

Specification of Letters Patent. Patented Feb. 22, 1921.

Application filed April 11, 1918. Serial No. 227,960.

To all whom it may concern:

Be it known that I, PERCY DE HAAS, a subject of the King of England, residing at 63 Highfield road, Rock Ferry, in the county 5 of Chester, England, have invented certain new and useful Improvements in or Relating to Disk Talking-Machines, of which the following is a specification.

This invention relates to disk talking machines, and has for its object to provide a machine (or a fitting to be applied to an existing machine) which will give a substantially continuous phonographic reproduction of sounds, so enabling lengthy 15 movements, such as overtures, and symphonies to be played without undesirable breaks.

This object is effected, according to my invention, by providing a plurality of turntables or mandrels for the records over which the stylus with its sound box successively travels, and means for automatically moving the reproducer from one record to another.

25 While the sounds are being reproduced phonographically from one record, the other record (or records) or record-carrier, may be running idle, and a record may, if desired, be changed without stopping the machine, this being an advantage as the reproducer may be brought into contact with a number of records in succession with very short intervals of silence between each; thus the attention required by the operator is 35 reduced.

In carrying my invention into practical effect, according to one arrangement, I provide a secondary spindle driven by belt, chain, toothed wheels, friction wheels, worm 40 gear, or otherwise, from the main driving spindle (or it may be driven by a separate and independent motor); which secondary spindle carries a turntable or support for a separate record. A single tone arm with 45 sound box or boxes articulated thereto is provided, and is adapted to move freely about its pivot, so that a stylus may be brought into contact with either the record disk on the turntable of the main spindle or 50 the record disk on the turntable of the secondary spindle.

To start the apparatus in a construction wherein a single motor actuates both main and secondary spindles, the main spindle is 55 set in motion by the driving motor, thus rotating the two records, and on the stylus

being brought into contact with one of them the sound is reproduced phonographically. At the end of the reproduction the tone arm is turned on its pivot and the stylus is 60 raised and brought into contact with the record on the other turntable, thus starting the sound reproduction from said latter record.

The record disk on the first turntable may 65 be removed and replaced by a new record while the record on the second turntable is being reproduced, so as to be ready for playing the moment the production of the second record is completed. Then the tone 70 arm may be turned back to its initial position to start the reproduction of the new record on the first turntable, and so the sound reproduction goes on almost continuously, if desired by the operator, or with 75 only very short intervals of silence.

The rising of the reproducer is, of course, readily arranged for, as, for instance, by providing the socket piece that carries the reproducer and the tone arm with elbows at 80 their adjacent ends which pivot into one another.

The arrangement for automatically moving the reproducer from one record to the next, and causing it to assume the starting 85 position on the second record, is characterized in that the tone arm, or part moving therewith or operated thereby of the machine carries a hinged or pivotal arm or bar located in such a position and disposed 90 at such an angle that at the end of the reproduction of one record the turning of the tone arm or other part about its pivot will have brought said pivotal arm into contact with the spindle (whereby the second record 95 is actuated) to produce a two fold action, namely (1) the displacement of said arm about its pivot, whereby—through a connecting cord or chain, levers, or the like—the reproducer is lifted off the first record; and 100 (2) the adhesion or pressure of said pivotal arm against said secondary spindle, whereby a traveling movement (like that imparted by a pinion to a toothed rack) is imparted to the former which carries the tone arm 105 and reproducer into the starting position for the second record, and allows the stylus thereof to be deposited gently on to said second record.

In order to provide sufficient adherence 110 or friction between said secondary spindle and said pivotal arm to make certain of the

latter partaking of the motion imparted to it by the former, I prefer to provide the surfaces of said arm and said secondary spindle with coverings of vulcanized fiber, 5 india rubber, or other suitable material, so as to insure their becoming frictionally adherent by contact.

To economize space, the secondary spindle is preferably so located that its turntable 10 overhangs the turntable of the main spindle, one record, therefore, being at a higher level than the other.

Means may be provided for throwing either turntable out of gear when the other 15 is working. Ball bearings may be fitted, if desired.

I may also provide means for adapting the apparatus to play records of variable sizes.

20 I will further describe my invention with the aid of the accompanying sheets of explanatory drawings which illustrate, by way of examples only, one mode of embodying same.

25 In said drawings:—

Figure 1 is a plan view, and

Fig. 2 an elevation, of a disk talking machine adapted for the successive playing of two records.

30 Fig. 3 represents in side elevation and end view an adapter sleeve for use in the playing of larger or longer records than usual.

The talking machine illustrated is of well known type, the mechanism for automatically causing the playing of a second record 35 being added.

Referring first to Figs. 1 and 2 of said drawings:—

1 represents the box or cabinet of the machine, 2 a turntable, and 3 a record disposed on said turntable 2; 4 indicates the tone arm revoluble about the spindle 5, 6 the sound box mounted on the U connecting tube or goose-neck 7 which is pivotally socketed in 45 the tone arm 4, and 8 is a stylus secured to the sound box 6: all as common in disk talking machines.

50 Mounted on the vertical spindle 9 which drives the turn-table 2 and is operated by a spring motor disposed within the cabinet 1 of the machine, is a grooved driving pulley 10, and secured on a second revolvable spindle 11 which carries a second turntable 12 is a grooved driving pulley 13: operatively connecting said pulleys 10 and 13 is a driving belt 14. Thus, when spindle 9—and with it turntable 1 and record 3—is rotated by the motor of the machine, motion is transmitted through said pulley 10, belt 60 14, pulley 13 and spindle 11, to second turntable 12, and the record 15 disposed on same.

65 Firmly clipped on said tone arm 4 is a bifurcated piece 16 whereto is hinged, by means of a connecting spindle 17, a bracket 18 which is normally prevented from up-

ward displacement by means of a spring 19, and is normally maintained in a horizontal plane above the spindle 11, so as not to contact therewith.

Pivotedly mounted on the end of said bracket 18 remote from its hinge is an arm 20, which is supported in a horizontal plane below the plane of the bracket 18, as shown in Fig. 2. For the purpose of connection with bracket 18, said arm 20 is provided with a pin or lug 21 whereon is secured a screw threaded spindle 22 which extends through a slot 23 formed in the bracket 18 and a passage in a plate 24, and is provided with a nut 25. Adjustment of said arm 20 75 relatively to bracket 18 may be effected by a rod 26, the engaging end whereof is secured to said spindle 22, said rod 25 being secured by a set screw 26A.

Secured to said pivotal arm 20 is one end 85 of a chain or like flexible connection 27, which is led over a pulley 28 mounted on a support 29 carried by bracket 18, the other end of said chain being attached to a disk 30 secured to a winged screw 31 which 90 passes through an arm 32 mounted on the U tube 7 and is secured by a nut 33. By slackening-back said nut 33 the screw 31 with disk 30 may be turned and adjustment of chain 27 effected. The inner face of said pivotal arm 20 is covered with a strip of rubber or other suitable frictional material 34 and the upper end of said spindle 11 is provided with a rubber sleeve 35.

As illustrated in the drawings, the parts 100 are positioned for the playing of the primary record 3, and in the consequent circular movement of the tone arm 4, bracket 18, and pivotal arm 20, the latter moves into contact with the sleeved spindle 11 just as the playing of this record is completed; and, through the frictional engagement of the inner face of pivotal arm 20 with the rotating spindle 11, the motion of said arm, bracket 18-tone arm 4 with U piece 7, and the reproducer 20 (comprising the sound box 6 and stylus 8) is continuous: at the same time, due to the angle at which said arm 20 is set, the arm in its travel is displaced about its pivot 22, and through its connection as before described, with the U piece 7, the latter is turned about its pivotal support on the tone arm 4 and the reproducer is raised clear of record 3 and moves over to the record 15. This is brought about 115 by the outer end of the arm 20 being swung outwardly or away from the bracket 18, due to said arm engaging the spindle and it is the turning or rotating of the spindle against said arm which causes it to swing 120 on its pivot even after the stylus 8 has been raised from the record.

When the pivotal arm 20 moves clear of the spindle 11, the stylus 8 is deposited on the second record 15 in position to commence 130

the reproduction of same, being lowered gradually through the shape or configuration of the inner face or rear end of the pivotal arm as shown in the drawings.

- 5 To install the attachment, the arm 4 is shifted until the stylus 8 lies in the inner or last sound groove of the record, and then the attachment is secured to the arm 4 with the arm 20 engaging the spindle 11. The flexible connection 27 is also adjusted so that the reproducer will be raised and lowered in proper timed relation to an actuation of the arm 20 by contact with the spindle 11.

Assuming that the stylus 8 is in the outer 15 or first groove of the record 3 and the machine is placed in operation, the tone arm 4 is gradually swung as the stylus 8 travels inwardly toward the center of the record 3. Since the bracket 18 is attached to the tone 20 arm 4 and the arm 20 pivotally attached to the outer end of the bracket 18, the bracket 18 in swinging toward the spindle 11 carries the pivoted arm 20 into engagement with said spindle which has a rolling action 25 against the arm 20. As the arm 20 encounters the spindle 11 the motion of the spindle causes the arm to move on the spindle and since the arm is pivoted relative to the bracket, it is obvious that the outer end of 30 the arm 20 will be swung relative to the bracket 18.

The initial contact of the arm 20 with the spindle 11 is such that the arm 20 receives an actuation pulling on the flexible connection 27 and this takes place as the stylus 8 reaches the inner or last sound groove of the record 3. In consequence of the flexible connection 27 being pulled upon the reproducer is elevated, and further travel of the 40 arm 20 against the spindle 11 causes the tone arm 4 and the bracket 18 to be swung whereby the reproducer is placed over the outer or first sound groove of the record 15. Since both of the records are driven in unison, the motion of the spindle 11 is dependent upon for the transfer of the tone arm from one record to the other, and after the tone arm is in position relative to the record 15, the angularity of the arm 20 is changed, 45 and the flexible connection 27 slackened to permit of the stylus 8 being lowered into the outer or first sound groove of the record 15, when there is a rendition of this record until the reproducer reaches the inner or last 50 sound groove of said record. It is during the playing of the second record 15 that the first or primary record 3 may be changed so that other records may be placed in position and rendered with very little interruption in the playing.

During the playing of the second record 15, the primary record 3 may be changed if desired so that three records may be reproduced with very little break in playing.

65 Referring now to Fig. 3 of the drawings,

if, for instance, the machine as illustrated is arranged to reproduce records of ten inches in diameter, and it be desired to play larger records of, say, twelve inches in diameter, an adapter or extension sleeve 36 may be 70 used which is designed to cause the reproducer to be extended to one side of the tone arm by one inch, thus enabling it to play a record two inches larger in diameter, as the stylus 8 will be lowered on to the secondary 75 record 15 at a distance of one inch farther from the secondary spindle 11 upon which the record revolves.

To apply said sleeve, the reproducer is removed from the U tube 7 and the larger 80 end of the sleeve 36 is pushed on to the end of same, so that said pin 37 may be locked into the customary bayonet slot provided in said tube. The reproducer is then fitted on the reduced end of said adapter, the customary pin provided on the reproducer being locked in the bayonet slot 38 of the adapter.

Having now described my invention what I claim as new and desire to secure by Letters Patent is:—

1. A disk taking machine embodying a plurality of turntables mounted on driven spindles, means adapted for operating the spindle, a pivotal tone arm and sound reproducer articulated therewith; a bracket secured to said tone arm, an arm pivotally mounted on said bracket; means adapted to operatively connect said pivotal arm and said reproducer, the arrangement being such that on the termination of the reproduction of one record said pivotal arm contacts with the turntable spindle of the second record whereupon said arm is moved so that it causes the reproducer, to be raised from the 100 first record and carried to and deposited in 105 position for playing on the second record.

2. In a disk talking machine, record carriers, means for operating said record carriers, a sound reproducer, means carried thereby and actuated by said carrier operating means adapted to transfer said reproducer from one record carrier to another.

3. A disk talking machine as characterized in claim 2, wherein the reproducer is elevated and lowered during its transfer from one carrier to the other.

4. In a disk talking machine, record carriers, means adapted to operate said carriers in unison, a sound reproducer, and means carried by the sound reproducer and actuated by one of said carriers adapted to transfer said sound reproducer from one carrier to the other.

5. In a disk talking machine, driven records, a tone arm and a reproducer common to said records, and means actuated from one of said records to transfer said tone arm and reproducer from one record to the other.

6. In a disk talking machine, driven rec-

ords, disposed in superposed planes with one record overlapping the other and driven therefrom, a tone arm and reproducer common to said records, and means actuated 5 from the overlapping record adapted to transfer said tone arm and reproducer from one record to the other.

7. A disk talking machine as characterized in claim 6, wherein said means includes an 10 arm which causes the tone arm to move in a lateral plane and the reproducer thereof to be raised and lowered.

8. In a disk talking machine, driven records, spindles centrally of said records, a 15 tone arm, a reproducer carried thereby, a bracket on said tone arm, an arm carried by said bracket and adapted to be swung by contact with one of said spindles, and means connecting said arm to said reproducer adapted for raising and lowering said reproducer.

9. In a disk talking machine, driven rec-

ords disposed in superposed planes with one record overlapping the other and driven therefrom, a spindle axially of the overlapping driven record, a tone arm common to said records, a reproducer carried by said tone arm, a bracket attached to said tone arm and extending over said overlapping record, an adjustable pivoted arm supported by said 25 bracket, and adapted for contact with the spindle of the overlapping record to cause said tone arm to swing from one record to the other, and means attached to said pivoted arm and to said reproducer adapted to raise and lower said reproducer in timed relation to the movement of said tone arm.

In testimony whereof I affix my signature in the presence of two witnesses.

PERCY DE HAAS.
